UNITED STATES PATENT OFFICE

160,790

CLOTHES HANGER

Harold G. Kongieser and Charles W. Weickers,
Worcester, Mass.

Application October 13, 1947, Serial No. 141,880

Term of patent 3½ years

(Cl. D33—8)

To all whom it may concern:

Be it known that Harold G. Kongieser and Charles W. Weickers, both citizens of the United States, both residing at Worcester, in the county of Worcester and State of Massachusetts, have invented a new, original, and ornamental Design for Clothes Hanger, of which the following is a specification, reference being had to the accompanying drawing, forming part thereof.

Fig. 1 is a side elevational view of a clothes hanger; and

Fig. 2 is a front elevational view thereof.

We claim:

The ornamental design for a clothes hanger, as shown.

HAROLD G. KONGIESER.
CHARLES W. WEICKERS.
